UNITED STATES PATENT OFFICE

2,420,962

INDUSTRIAL FURNACE

Fred H. Loftus, Mount Lebanon, Pa.

Application September 8, 1943, Serial No. 501,526

13 Claims. (Cl. 263—40)

1

My invention relates to industrial furnaces, and is particularly directed to certain new and useful improvements in furnaces for heating elongate blanks or work pieces of aluminum, preparatory to a forging or rolling operation. The invention will be described as it has been developed for such particular field of service, with the understanding that within the terms of the appended claims various other fields are within the contemplation of the invention.

In the accompanying drawings Fig. I is a fragmentary view of a furnace installation in which the invention has in exemplary way been embodied, and Fig. II is a view of the installation in transverse vertical section. Fig. I appears partly in plan and partly in horizontal section on the plane I—I of Fig. II, while Fig. II, drawn to larger scale, shows the furnace in vertical transverse section, on the plane II—II of Fig. I.

Referring to the drawings, the furnace installation in which the invention is herein illustrated comprises a pit furnace having side walls 2, 2, end wall 3, 3, and a floor 4 constructed of refractory masonry, externally sheathed in steel plate 5 and reinforced and tied by means of steel buckstays 6 that are anchored at their lower ends to a concrete foundation 7. The pit 8 is closed from above by means of a cover 9 adapted to swing on an axis 10 between open and closed positions, and in closed position the cover cooperates with a pit-encompassing seal 11, to provide a substantially air-tight chamber in which the material to be heated or heat treated is enclosed. The cover is power operated, but the means to this end, as well as the specific details of the cover-sealing structure, are not an immediate concern of my present invention, and for this reason will not be described in detail.

Inlet ports 12 are provided in opposite walls of the furnaces for introducing hot gases or burning columns of fuel into the chamber or pit 8, and it will be noted that such inlet ports are located adjacent to the top or cover of the chamber. In this case the inlet ports 12 are provided in the opposite side walls 2, 2; the ports are spaced apart longitudinally of such side walls, as appears in Fig. I; and the fuel is preferably, though not necessarily, burned at a point remote from the ports, rather than being admitted immediately to the furnace chamber by means of burners located in the ports.

More particularly, the fuel is burned in a combustion chamber 13 removed from the furnace structure proper, and the hot products of combustion are propelled by means of a fan 22 (driven

2

by an electric motor 23) through a passage 24 into a flue 14 equipped with a damper 15. The flue 14 is the inlet flue of the furnace. It comprises a tunnel flue that extends longitudinally beneath the chamber or pit 8 of the furnace, and from such tunnel flue passageways 16 lead through the furnace hearth and side walls to the inlet ports severally. The passageways 16 are provided with dampers 16a which afford control of the hot gases flowing into the furnace chamber. The hot products of combustion delivered into the furnace chamber, at uniformly distributed points longitudinally thereof, sweep over and between the pieces of work to be heated—in this case bars B of aluminum—and find escape in outgo ports 17.

The outgo ports 17 are formed in the floor 4 of the furnace chamber, and are spaced apart on the longitudinal center-line thereof. An outlet tunnel flue 19 extends longitudinally beneath the furnace chamber, and to this flue the outgo ports deliver the exhaust gases by way of passageways 18. The tunnel flue 19 extends from the furnace to a point adjacent to the remotely situated combustion chamber 13, and a duct 20 affords communication between flue 19 and the combustion chamber. A burner 21 is arranged to direct fluid fuel and air into the combustion chamber, and under the propulsion of fan 22, a continuous circulation of hot gases is established and maintained. The hot gases generated by the combustion of fuel are delivered into the tunnel flue 14, whence they stream to and through the passageways 16 and ports 12 into the furnace chamber 35 containing the work to be heated.

As will presently appear in greater detail, the billets or bars B of aluminum that constitute the furnace charge are positioned in a cradle 25 of skeleton construction, and the individual bars 40 are supported in spaced relation. The hot gases streaming into the top of the furnace chamber pass downward through the spaces between the bars B of the charge and enter the outgo ports 17, whence they flow through the outgo flue 19 and return to the combustion chamber 13. The hot gases flowing through the furnace chamber yield large quantities of heat to the furnace charge, and upon returning to the combustion chamber 13 the heat thus yielded by the gases is 50 restored by the burning fuel. In this way, the residual heat in the gases leaving the work-heating chamber 8 of the furnace is conserved, and the thermal efficiency of the installation maintained at maximum value. A quantity of gas is 55 bled from the continuously circulating stream,

and such quantity is equal to the quantity of hot gases generated by the combustion of fuel injected by the burner 21. A vent 26 including a valve 27 is provided at the cool end of the combustion chamber, the end into which the gases returning from the furnace enter the combustion chamber, and this vent provides for the bleeding away of the excess gas. The adjustment of the valves 15 and 28 in the flues 14 and 19, respectively, together with the adjustment of the bleeder valve 27, and the regulation of the speed of the fan and the rate of combustion within the chamber 13, affords the desired control of the circulating hot gases, and of the heating effect of the furnace. The adjustment of the dampers 16a, that individually control the flow of the hot gases to the inlet ports 12, provides for the regulation of the heating effect longitudinally of the furnace chamber. Uniform heating conditions throughout the extent of the furnace chamber are obtained.

Having described furnace structure per se, attention will now be directed to the improved support for the work to be heated. A problem in the heating of a batch of articles, such as the bars B, has been to provide a uniform flow of the hot gases over the surfaces of all of the articles; that is, a flow of gases that will afford uniform heating effect throughout all of the furnace charge. The cradle 25 affords a solution of this problem.

As already mentioned the cradle 25 is of skeleton construction. More particularly, the cradle is formed of a plurality of W-shaped frame members (Fig. II) to which the reference numeral 25 is immediately applied. These frame members are spaced apart to provide an elongate cradle for the bars to be supported, and are integrated by means of sections 29 of I-beams extending in parallelism between the successive members 25 and being welded thereto at the bottoms of the two V's of the W. The members 25 are further united and reinforced by means of longitudinal tie-rods 30 extending between the side arms of said W-shaped frame members, as may be understood upon comparing Figs. I and II. The bodies or limbs of the W-shaped members 25 are of I-shape in cross section, and are provided at the upper ends of the limbs with eyes 31, whereby the cradle may be engaged by a crane and lifted with its load of work pieces B into and from the furnace chamber. The cradle structure is formed of cast iron or steel, a material of adequate strength under the effect of the heat to which the aluminum bars B are subjected.

In this case, the bars B are of a length that approximately equals the length of the furnace chamber, and the bar-supporting cradle is of commensurate length. In Fig. I the bars and the cradle are shown fragmentarily, in order that the arrangement of the outgo ports 17 in the floor of the furnace chamber may be seen in plan. It will be understood that in case the bars are of shorter length, say half of the length of the furnace chamber, the cradle may be made in two sections, each loaded with bars and arranged end to end in the furnace chamber. The cradle sections may be individually removed from the furnace for unloading and loading.

The bars B are loaded in the cradle in rows that are spaced apart by means of spacer rods 32, and in the individual rows the bars are also spaced apart.

The particular form of the work-supporting

cradle, together with the spaced arrangement of the billets or bars B supported therein, provides for an uniformly distributed flow of the hot gases through the group of supported bars. The spaces between the bars serve in effect as flues through which the hot gases, delivered by the ports 12, stream on their way to the outgo ports 17. The W-like arrangement of the group of bars is instrumental in establishing a uniform pressure drop through all of the devious paths of flow of the hot gases, whereby substantially the same quantity of hot gases flows through each of the paths, with the consequence that the heating effect is uniformly distributed to all of the bars in the cradle.

In addition to the described arrangement of the group of bars to be heated, another important feature is to be noted. The sections 29 of I-beam, that interconnect the frame members 25 of the cradle, form, when the cradle is in position of service upon the hearth of the furnace, parallel curtain walls that extend longitudinally of and on opposite sides of the line of outgo ports 17. These curtain walls prevent a short-circuit flow of the hot gases beneath the charge of bars B to the outgo ports. See the arrows in Fig. II that indicate the flow of the gases.

Still another feature merits particular consideration. It will be observed that the central portions of each W-shaped frame member 25, that is, the portions that form the inverted V of the W, support the work in such position that a longitudinally extending flue is provided above the outgo ports 17. That is to say, the inverted V portions of the W-shaped frame members 25 are centered with respect to the line of outgo ports, and form with the bodies of the supported bars B a flue into which the gases streaming through the spaces between the bars pass on their way into the outgo ports 17. The provision of such flue, particularly in conjunction with the curtain walls 29, contributes to the realization of the desired distribution of gaseous flow through the body of the furnace charge.

It will be understood that various modifications of the structure described may be adopted without departing from the spirit of the invention defined in the appended claims.

I claim as my invention:

1. A furnace including a work-containing chamber, a tunnel flue extending under the furnace chamber, means for supplying hot gases to such flue, inlet ports opening through a wall of the furnace chamber at spaced-apart points in the horizontal extent thereof, passageways extending from said flue to said ports, a second tunnel flue extending parallel to the first tunnel flue under the furnace chamber and communicating with an outlet for waste gases, outgo ports opening from the said chamber at spaced-apart points, and passageways for waste gases leading from said outgo ports to said second tunnel flue.

2. A furnace including a work-containing chamber, a tunnel flue extending under the furnace chamber, means for supplying hot gases to such flue, inlet ports opening through the opposite side walls of the chamber at spaced-apart points in the longitudinal extent of such walls, passageways extending from said flue to said ports, a second tunnel flue extending parallel to the first tunnel flue under the furnace chamber and communicating with an outlet for waste gases, outgo ports opening in the floor of the furnace chamber at spaced-apart points in the horizontal extent thereof and passageways for

waste gases extending from said outgo ports to said second tunnel flue.

3. A furnace including a work-containing chamber, a tunnel flue extending under the furnace chamber, means for supplying hot gases to such flue, inlet ports opening through the opposite side walls of the furnace chamber at spaced-apart points in the longitudinal extent of such wall and adjacent to the top of said furnace chamber, passageways extending downward in the furnace structure and establishing communication between said ports and said tunnel flue, a second tunnel flue extending parallel to the first tunnel flue under the furnace chamber and communicating with an outlet for waste gases, outgo ports opening through said floor at spaced-apart points in a longitudinal extent thereof, and passageways for waste gases leading from said outgo ports to said second tunnel flue.

4. A pit furnace including a work-containing pit, a tunnel flue extending under the pit, means for supplying hot gases to said flue, inlet ports opening through the opposite side walls of the pit, said inlet ports being located adjacent to the top of the pit and being spaced apart in the longitudinal extent of said side walls, a second tunnel flue extending under said pit, outgo ports opening through the floor of said pit below said ports and at spaced-apart points in the horizontal extent thereof, and passageways for waste gases leading from said outgo ports to said second tunnel flue.

5. A pit furnace including a work-containing pit, a tunnel flue extending under the pit, means for supplying hot gases to said flue, inlet ports opening through the opposite side walls of the pit, said inlet ports being located adjacent to the top of the pit and being spaced apart in the longitudinal extent of said side walls, a second tunnel flue extending under said pit, outgo ports opening through the floor of said pit below said ports and at spaced-apart points in the horizontal extent thereof, and passageways for waste gases leading from said outgo ports to said second tunnel flue, means in said pit for supporting a plurality of pieces of work in spaced-apart relation athwart the paths of flow of hot gases streaming from said inlet ports to said outgo ports.

6. A pit furnace including a work-containing pit, a tunnel flue extending under the pit, means for supplying hot gases to said flue, inlet ports opening through the opposite side walls of the pit, said inlet ports being located adjacent to the top of the pit and being spaced apart in the longitudinal extent of said side walls, a second tunnel flue extending under said pit, outgo ports opening through floor of said pit at spaced-apart points in the horizontal extent thereof, and passageways for waste gases leading from said outgo ports to said second tunnel flue, means in said pit for supporting a plurality of pieces of work in spaced-apart relation athwart the paths of flow of hot gases streaming from said inlet ports to said outgo ports, said last means comprising a cradle of skeleton construction and of W shape in cross section.

7. A pit furnace including a work-containing pit, a tunnel flue extending under the pit, means for supplying hot gases to said flue, inlet ports opening through the opposite side walls of the pit, said inlet ports being located adjacent to the top of the pit and being spaced apart in the longitudinal extent of said side walls, a second tunnel flue extending under said pit and com-

municating with an outlet for waste gases, outgo ports arranged in spaced-apart relation on the longitudinal center-line of the pit floor, passageways for waste gases leading from said outgo ports to said second tunnel flue, and a cradle for supporting a plurality of pieces of work, said cradle being of skeleton construction and of W-shape in cross section and arranged in said pit with the inverted V of the W centered with said line of outgo ports.

8. A furnace including a work-containing chamber, means for delivering a stream of hot gases into said chamber, an outgo port opening through the floor of said chamber for leading waste gases therefrom, and a cradle of skeleton construction for the support of a plurality of pieces of work in said chamber, said cradle being of W-shape in cross section, with the inverted V of the W positioned over said outgo port.

9. A furnace including a work-containing chamber, inlet ports for introducing hot gases through the opposite side walls of said chamber at spaced-apart points in the longitudinal extent thereof, outgo ports opening through the floor of the chamber at spaced-apart points in the extent of the center-line thereof, and a cradle of skeleton construction and W shape in cross section for supporting a plurality of pieces of work in said chamber, said cradle being arranged with the inverted V of the W centered with respect to said center-line.

10. A furnace including a work-containing chamber, inlet ports for introducing hot gases through the opposite side walls of said chamber at spaced-apart points in the longitudinal extent thereof, outgo ports opening through the floor of the chamber at spaced-apart points on the center-line thereof, and a cradle of skeleton construction for supporting a multiplicity of pieces of work in spaced-apart relation in said chamber, said cradle being formed of material of higher resistance to heat than the pieces of work contained therein, said cradle being formed to provide in conjunction with the supported pieces of work a flue above the outgo ports in the floor of said pit.

11. A furnace including a work-containing chamber, inlet and outlet flues extending under the furnace chamber, a plurality of inlet ports opening through a wall of the furnace chamber at spaced-apart points in the extent thereof, passageways extending from said inlet flue to said inlet ports, a combustion chamber connected to deliver hot products of combustion into the inlet flue, a plurality of outgo ports opening from the furnace chamber, passageways connecting said outgo ports to said outlet flue, a passage from said outlet flue to said combustion chamber, means for supplying fuel to said combustion chamber, means for propelling products of combustion from said combustion chamber through said inlet flue to said inlet ports and into the furnace chamber, from said furnace chamber through said outgo ports into said outlet flue, and from the outlet flue back into said combustion chamber, and means for bleeding spent gases from such circulating stream of gases.

12. A furnace including a work-containing chamber having a line of outgo ports opening through the floor of the chamber for the escape of exhaust gases, means for supplying work-conditioning gases to said chamber, a work-support of skeleton construction for supporting a plurality of pieces of work in said chamber, said work-support including portions which, with the

work-support in service position within the furnace chamber, form baffles that extend longitudinally of and on opposite sides of said line of outgo ports, to provide within the loaded work-support, the effect of a flue extending along said line of outgo ports.

13. A furnace including a furnace chamber, means including inlet ports for introducing hot gases to said chamber, outgo ports for leading gases away from the chamber, and means for supporting a group of elongate articles spaced apart and extending horizontally across the lines of flow of the hot gases streaming from said inlet ports to said outgo ports, said means being constructed to support said spaced-apart articles, with the cross-sectional extent of the group decreased toward the bottom of the group, whereby

a plurality of gas-conducting passages having substantially uniform flue losses are formed by and between the spaced-apart articles.
